Des. 838

John Gott, of Albany, N.Y.
Letters Patent, No. 838, October 7, 1856.

The schedule referred to in these Letters Patent and making part of the same.

Be it known that I, John Gott, of the City of Albany, and State of New York, have produced a new and original design, being a Bust of Colonel John C. Fremont, of which the annexed delineation forming part of this specification is a correct exhibition and representation. What I claim and desire to secure by Letters Patent of the United States, is the new and original design of a Bust of Colonel John C. Fremont, as set forth in the above specification.
